UNITED STATES PATENT OFFICE

CHARLES SUTTLEFFE WHITE, OF LONG BEACH, CALIFORNIA, ASSIGNOR OF FIFTEEN PER CENT TO JAMES E. OGDEN AND FIFTEEN PER CENT TO WILLIAM J. SCHEUSS, BOTH OF COMPTON, CALIFORNIA

AMALGAMATOR

Application filed September 26, 1928. Serial No. 308,464.

This invention relates more specifically to an amalgamating apparatus for the recovery of fine gold from sands and ores.

The primary object of the invention is to provide an apparatus which will efficiently extract values from ores or gold bearing sands in which the gold is present in free but minute particles, commonly known as "flour" gold.

Briefly stated the invention resides in a semi-circular trough or table member horizontally disposed and slightly inclined from the feed to the discharge end and is adapted to be continuously oscillated, such action causing the values to be liberated from the sands which are then discharged through a plurality of openings in the bottom of the trough into a similar trough located directly below and connected therewith, the second trough being provided with a plurality of amalgam pockets which recover the values from the sands or other materials being operated upon. The invention also resides further in such other novel features of construction as may be herein disclosed.

In the accompanying drawings wherein certain embodiments of the invention are disclosed by way of illustration;

Fig. 1, is a top plan view of the amalgamating machine.

Fig. 2, is a vertical sectional view taken on line 2—2 of Fig. 1.

Fig. 3, is a front elevation taken in the direction indicated by the arrow 3 of Figs. 1 and 2.

Fig. 4, is a rear elevation taken in the direction indicated by the arrow 4 of Figs. 1 and 2.

Fig. 5, is an enlarged fragmentary plan view.

Fig. 6, is a section taken on line 6—6 of Fig. 5.

Fig. 7, is a section taken on line 7—7 of Fig. 6.

Fig. 8, is a fragmentary plan view of the second trough.

Referring by numerals to the drawings, 10 designates the upper trough which is semi-circular in cross section and of considerable length relative to its width, and is pivotally mounted adjacent its forward and rear ends

by pins 11 which extend through openings 12 in bearing blocks 13, which in turn are carried by pins 14 set at right angles to the pins 11, the pins 14 extending through openings in the bearing blocks and in the yokes 18 which are secured to cross bars 19 and 20 of frames generally designated at 22 and 23 respectively. The pins 11 are carried by standards 24 which are secured to cross bars 26 extending across the top and secured to the sides of the trough. By means of the above described construction the trough may be oscillated on the axis of the pins 11.

The cross bar 19 of the frame 22 is rigidly supported by standards 28 whereas the cross bar 20 of the frame 23 is carried by uprights 30 of a structure 31 having vertically disposed bars 32 slidably in rigidly mounted channels 34.

By the arrangement of the pins 14 the inclination of the trough 10 may be varied by raising or lowering the rear end 35 of the trough by screws 36 having heads 37 rotatable in sockets 38 secured to the horizontal bar 39 of the structure 31 and threaded through plates 40 on the upper ends of the channels 34.

The sands or ores which have been previously reduced by crushing and grinding are continuously fed through a launder 42 into the forward end of the trough 10 by any suitable feeding apparatus not shown. The sands are delivered to the machine wet, however additional water may be supplied through pipe 44. The sands are discharged from the trough 10 through a plurality of evenly spaced openings 46 into a second trough 50 wherein the values are recovered by contact with the mercury. The trough 50 is positioned directly below the trough 10 and is secured thereto by brackets or hangers 52.

Due to the inclination and oscillation of the trough 10 the sands or other material continuously move toward its lower end, the action of which is somewhat retarded by a plurality of screens 53 of approximately one-fourth inch mesh placed on the bottom of the trough 10 adapted to collect the coarser metallic values in the sands between the

meshes of the screen, the sands being directed toward the openings 46 by converging baffle plates 54. The discharge area of the openings 46 may be quickly regulated by closures 56 slidably mounted in guides 57 secured to the bottom of the trough as clearly shown in Figs. 6 and 7.

The discharge area of the openings 46 is regulated by the closures 56 so that an approximately equal amount of sand is discharged through each opening, also providing sufficient total area to permit discharge of all the sands from the trough 10 into the trough 50. In order to prevent any sand running past the last discharge opening 46 a vertically disposed plate 58 is provided, all of the openings being maintained opened and free from clogging by a plurality of blades 60 secured to a shaft 61 mounted in bearing 62, the lower end of each blade extending into the openings and agitating the materials passing through the openings.

These blades are held in a vertical position by a pair of opposed coil springs 63 one end of each of which is secured to the upper end of a lever 64 keyed to the shaft 61, the other ends of the springs being connected to brackets 65 on the cross bar 20 of the structures 31.

It will be seen that as the trough is oscillated the openings 46 will be kept free by the blades remaining stationary due to the action of the springs 63.

The trough or table members are oscillated by a pitman 66 one end of which is connected by a pin 67 to a crank 68 on a shaft 69, the other end of the pitman being connected to the lower end of a lever 70, the upper end of which is secured to the bottom of the trough 10. The tilting range of the trough may be varied by changing the stroke of the pitman which is accomplished by moving the crank pin 67 into any one of the openings 68^a on the crank. If it becomes necessary to tilt the trough in a greater range than the width of the openings 46 the blades 60 will yield due to the mounting of the springs 63, thus preventing a breaking or dislodgment of the same. The shaft 69 is mounted in bearings 72 and may be rotated through a suitable speed reducing unit generally designated at 73.

As previously referred to the values are extracted in the lower trough 50 by contact with mercury. A plurality of pockets 75 are formed in the bottom of the trough 50 the sides of which are flared as indicated at 76 and terminate in short tubes 77, the pockets being partially filled with mercury and closed by screw caps 78, by means of which the amalgam may be quickly removed after an operation.

Due to the pivotal mounting of the trough at each end above the center thereof, a swinging or oscillating movement is effected the

action of which causes the mercury in the second trough to be thrown against the sides, thereby bringing it into contact with the sand resulting in a high extraction of values therein. The movement of the sands toward the lower end of the trough 50 is retarded by accurate baffle plates 79 and are finally discharged through the spout 80.

I claim:

1. An amalgamating apparatus comprising a semi-circular trough, means for pivotally supporting said trough for lateral oscillation on centers located directly above said trough, a second semi-circular trough below said first trough and connected thereto, said first trough having a plurality of openings in its bottom, screens on the bottom of said trough between said openings adapted to collect the coarser particles of the values in the sands passing thereover, said second trough having a plurality of pockets holding a quantity of mercury adapted to recover the remaining values in the sands passing through the openings in said first trough, and means for oscillating or swinging said troughs.

2. An amalgamating apparatus comprising an elongated inclined semi-circular trough having a plurality of openings in its bottom, a second semi-circular trough directly below and rigidly connected to said first trough, pivot pins projecting from standards secured to said first trough adjacent each end thereof, said pivot pins extending into openings in supporting members positioned above the radial center of said first trough, a plurality of screens resting on the bottom of said first trough between the openings therein adapted to collect the coarser metallic values in the sand passing thereover between the meshes of the screen, said second trough having a plurality of pockets having flared sides adapted to hold a quantity of mercury, and means for oscillating said first and second troughs laterally on said pivotal pins, whereby the mercury in the pockets of said second trough will be sloshed against the sides thereof to recover the values in the sands discharged through the openings in said first trough into said second trough.

In testimony whereof I affix my signature.

CHAS. S. WHITE.
